A. W. KNUTSON:
STANCHION HEAD.
APPLICATION FILED MAY 11, 1917.

1,246,758.

Patented Nov. 13, 1917.

UNITED STATES PATENT OFFICE.

ALFRED WM. KNUTSON, OF GALESBURG, ILLINOIS, ASSIGNOR TO ROWE MANUFACTURING CO., OF GALESBURG, ILLINOIS, A CORPORATION OF ILLINOIS.

STANCHION-HEAD.

1,246,758.

Specification of Letters Patent. Patented Nov. 13, 1917.

Application filed May 11, 1917. Serial No. 167,951.

To all whom it may concern.

Be it known that I, ALFRED W. KNUTSON, a citizen of the United States, and a resident of Galesburg, in the county of Knox and State of Illinois, have invented a new and useful Stanchion-Head, of which the following is a specification.

My invention relates to heads for stanchions the respective members of which interlock and which are instantly separable.

One of the objects of the invention is to improve, in several respects hereinafter stated, stanchion-heads of the type disclosed in my United States Patent No. 1,216,327, issued February 20, 1917. In heads of said type there has heretofore been constant danger that the edge of the hand of the operator would be pinched between the forked guide-handles and the stall-post which they straddle, as it is a common thing for him to hold on to the handles until he has positioned them. One of the improvements is directed toward eliminating this danger.

Another object is to provide a novel adjustable head, in which the improvements above referred to are incorporated and with which they coact.

To provide novel structural features and novel arrangements and combinations of the several elements entering into my improvements is an object.

Concisely stated it may be said that the principal object of the invention is to generally improve the construction and to increase the utility and efficiency of devices of this character.

In the accompanying drawings, which illustrate a preferred embodiment of the invention:

Figure 1 is a rear elevation showing a stall in which is hung a stanchion in which my improvements are incorporated;

Fig. 2, a longitudinal vertical section of a portion of the left hand part of the head;

Fig. 3, a similar view of a portion of the right hand side of the head;

Fig. 4, a transverse vertical section, taken in the plane of the lines 4-4 in Figs. 3 and 6;

Fig. 5, a horizontal section of a portion of the left hand part of the head;

Fig. 6, a plan, partly in horizontal section; and

Fig. 7, a detail of one of the handles.

Considering the drawings in detail and indicating the elements and, where necessary, the parts thereof each by a distinguishing numeral, uniformly employed, 2 indicates a stall-curb; 3, a stanchion-supporting rail; and 4, 4, stall-posts secured to said curb and supporting said rail. 5 denotes a curb-link; 6, a yoke pivoted therein and having eyes through which move the links of a chain 7 the respective ends of which are attached, by means of arms 7', to the stanchion-adjusting bar 8 which is adjustable, by means of bolts 9, in the lower ends of the stanchion-arms 10, 11. Said parts are not claimed herein as new.

Secured to the rail 3 is an adjusting bracket 12 having pockets either of which is adapted to receive the mushroom head 13 of a coupling 14 in which is adjustably mounted a tubular supporting arm 15, adapted to be locked therein by a bolt 16. 70 This locking feature is shown, described and claimed in a copending application filed by me of even date herewith, for joint or coupling and is not specifically claimed herein. Said arm 15 is adjustably mounted 75 also in an eye 17 in the upper end of the arm 10, and also in the eye 18 of the locking head by bolts 19 and 20 respectively, as will be more fully presently described. It may be stated at this time, however, that 80 parts of the adjusting and locking mechanisms just referred to are disclosed also in my above named copending application.

21 indicates a head the inner end of which has the eye 18 above noted. One of its 90 pendent, spaced cheeks 22 is provided with an aperture 23 which receives the bolt 20.

A transversely inclined way 25 adapted to be traversed by a nut 26 engaging the bolt 20, is formed in the bottom of the head. A 95 boss 27 projects inwardly from the upper wall of the head and seats in an opening 28 in the arm 15. When the arm 15 has been positioned the operator will turn the bolt 20 to further thread it through the nut 26. As 100 the bolt-head is held from movement, the nut will thus be caused to travel up the in-

clined way 25, the latter forcing it against the arm 15 and consequently forcing said arm into locking frictional contact with the upper wall or top of the head 21. The boss 27 5 and aperture 28 serve not only as guides in positioning the arm 15, but also they aid in holding it in place should the bolt 20 become loosened. Hinged at 30 between pairs of ears 29 at the rear end of the head are a pair 10 of operating-levers 31 the front end of each of which constitutes a stop 32 and the rear portion of each of which constitutes a handle. 33, 33 designate springs one end of each of which seats in a pocket 34 in the front end of the coacting lever and the other 15 end of which fits over a boss 35 in the upper wall of the head.

36 indicates a sliding connection, hinged by a bolt 37 to the crown of the stanchion 20 arm 11 and having at its outer end a rigid, integral fork 38 adapted to straddle the adjacent stall-post 4. Its elongated fore-portion is preferably L-shaped in cross section and is provided at its terminal with stop- 25 flanges 39, which, should the connection be drawn out to its limit in operation, strike the shoulders 40 on the locking handles 31. Dispensed on each side of the web of the connection and arranged near said shoulders 40 30 is a lug 41. Projecting upward from the connector is a thumb-piece 42 for a purpose presently described.

Assume the parts to be in the relative positions shown by full lines in Figs. 1 and 5. 35 To release the connection 36 the operator has but to squeeze toward each other the outer ends of the locking handles 31, thus bringing them to the dotted line position shown in Fig. 5, and to simultaneously press 40 outwardly with his thumb on the thumb-piece 42 to release the connection 36 from the head 21. Said movement of the elements 31 removes the shoulders 40 from position to lock the lugs 41 of the connection, and the 45 pressure of the operator's thumb on the projection 42 causes the connection and thereby the stanchion arm 11 to move to the dotted line position shown in Fig. 1. If the stanchion be in line transversely of the stall 50 the fork 38 will automatically straddle the post 4, and if it be off line said fork may be readily guided to position. There will be no danger of injury to the operator's hand, for it does not follow the fork. It is to be noted 55 also that the operations of squeezing toward each other the elements 31, whereby to release the connection 15, and of pressing on the projection 42 to start the connection to moving out of the head 21, are performed by 60 one hand, and that therefore a one-handed man may operate the device as well as one possessing both hands.

A tongue-like projection 43 on the terminal of the connection 15 prevents, by catch-

ing on the shoulders 44 formed by the inner 65 terminals of the cheeks 29, accidental removal of the connection, even though the shoulders be separated to let the flanges 39 pass, but if it be desired to remove the connector from the head it may be readily done 70 by tipping the outer end of the connector downward, allowing the projection 43 to pass over the tops of said shoulders.

The absence of the usual large number of bolt-heads, nuts and similar projecting elements, all of which are liable to injure the animal confined in the stanchion, is to be noted. The construction shown is one in which the elements present almost uniformly smooth surfaces and further in which but 80 few bolts and nuts are required.

For the purposes of this specification I shall herein consider the arm 10 as a relatively stationary one, and the arm 11 as being movable with reference thereto. Also, I 85 shall herein consider the connector 15 as the movable member of the locking head, and the member 21 the stationary member of the head.

Having thus set forth the nature of the 90 invention I claim as new the following, to-wit:

1. In a stanchion, a locking head comprising as one element a relatively stationary member, connector-locking elements 95 mounted in the said member, and a connector comprising the other member of the head, mounted to slide in said stationary member and to be locked therein by said locking elements, said connector provided on its outer end with a post-engaging fork which lies normally between portions of the connector-locking elements.

2. In a stanchion, a locking head comprising as one element a relatively stationary member, connector-locking elements associated with the said member, and a connector comprising the other member of the head, mounted to slide in said stationary member and to be locked therein by said locking elements, said connector provided 105 on its outer end with a post-engaging fork which lies normally between portions of the connector-locking elements.

3. In a stanchion, a locking head comprising as one element a relatively stationary member, connector-locking elements mounted in the said member, and a connector comprising the other member of the head, mounted to slide in said stationary 110 member and to be locked therein by said locking elements, the connector having at its outer end a post-engaging fork which lies normally between portions of the connector-locking elements.

4. In a stanchion, and in combination with stall-posts, a relatively stationary stanchion-arm, a stanchion arm movable with refer-

ence to said arm, a relatively stationary locking-head member, means for connecting it with the first recited arm, locking elements associated with said head-member, and a connector constituting the other head-member, adapted to be locked in the first recited head-member by said locking elements and having a fork adapted to engage one of the stall-posts, said fork lying normally between the extended portions of said locking elements.

5. In a stanchion, and in combination with a stall-post, a pair of stanchion-arms movably connected at their lower ends, a locking-head-member connected with one of them, locking elements associated with said member, and an element including a post-engaging fork, connected with the other stanchion arm and adapted for engagement by said locking elements, the locking elements lying at the sides of and tending to prevent the operator's hands from coming in contact with the fork.

6. In a stanchion, and in combination with a stall-post, a pair of arms movably connected at their lower ends, a locking-head-member connected with one of them, divergent locking-levers associated with said member, and an element including a post-engaging fork, connected with the other stanchion arm and adapted to move in said head-member and to be locked therein by said locking elements, said fork lying normally between the divergent portions of said levers.

35 7. In a stanchion, and in combination with the arms thereof, a locking-head-member, a pair of divergent pivoted locking-levers, a connector secured to the other arm and having at its outer end a stall-post-engaging fork, said locking-levers adapted to lock the connector in said head-member and their divergent portions lying normally each at the outer side of one of the limbs of the fork.

45 8. In a stanchion, and in combination with a stall-post, a relatively stationary stanchion-arm, a stanchion-arm movable relatively thereto, a locking-head-member connected with the stationary arm, locking elements hinged in said head-member and their outer ends constituting normally divergent handles, a connector adapted to be locked by said locking elements, said connector having a post-engaging fork lying normally between said divergent handles, and means for securing the connector to the movable stanchion-arm.

9. In a stanchion, a relatively stationary stanchion-arm, a relatively movable stanchion-arm hingedly connected thereto at its lower end, a supporting arm secured to the stationary arm, a locking-head-member slideable on the supporting-arm, means for forcing the supporting-arm into frictional con-

tact with the upper wall of said locking-head-member, and a locking-head-member carried by the movable stanchion-arm and adapted to engage the other locking-head-member.

10. In a stanchion, a relatively stationary stanchion-arm, a relatively movable stanchion-arm connected thereto at its lower end, a supporting-arm secured to said stationary arm, a locking-head-member slideable on the supporting-arm and provided with an inclined way, a nut adapted to traverse said way, a bolt engaging the nut and adapted to cause it to travel upwardly on said way to thereby force said nut against the supporting-arm and the arm against the locking-head-member, and means coöperating with said locking-head-member for locking the movable stanchion-arm therein.

11. In a stanchion, and in combination with a stall-post, a tubular stanchion-supporting-arm, a relatively stationary stanchion-arm supported thereby, a locking-head-member also supported thereby, a stanchion-arm hingedly connected at its lower end to the stationary stanchion-arm, a stall-post-engaging member carried by the movable stanchion-arm and adapted to be secured in said locking-head-member, and locking-and-releasing elements hinged to one of the head members and adapted to engage the other, said locking-and-releasing elements having extensions between which the stall-post-engaging member normally lies.

12. In a stanchion, and in combination with a stall-post, a tubular stanchion-supporting-arm, a relatively stationary stanchion-arm supported thereby, a locking-head-member also supported thereby, locking members hinged to said locking-head-member, their outer portions forming divergent handles, a locking-head-member slideable in the first recited locking-head member and in said tubular element and adapted to be locked by said locking elements, its outer end constituting a post-engaging fork disposed between said divergent handles, and means for securing the slideable locking-head-member to the movable stanchion-arm.

13. In a stanchion, and in combination with a stall-post, a tubular stanchion-supporting-arm, a relatively stationary stanchion-arm supported thereby, a locking-head-member also supported thereby, locking elements hinged to said locking-head-member, their outer portions forming divergent handles, a locking-head-member slideable in the first recited locking-head member and in said tubular element and adapted to be locked by said locking elements, its outer end constituting a post-engaging fork disposed between said divergent

handles, and means for hinging the slidable locking-head-member to the movable stanchion-arm.

14. Combined in a stanchion, stanchion-arms one of which is adapted to swing, means for flexibly connecting them at their

lower portions, locking-elements whereby their upper ends may be secured to each other, and a stall-post-engaging member lying normally between portions of said locking elements. 10

ALFRED WM. KNUTSON.
